US00D989761S

(12) **United States Design Patent** (10) **Patent No.:** **US D989,761 S**
(45) **Date of Patent:** **** Jun. 20, 2023**

(54) **COMMUNICATION DEVICE**(71) Applicant: **Motorola Mobility LLC**, Chicago, IL (US)(72) Inventors: **Poliana Feliconio Pereira**, San Paulo (BR); **Mark Finney**, Chicago, IL (US); **Joel Soto**, Maywood, IL (US)(73) Assignee: **Motorola Mobility LLC**, Chicago, IL (US)(**) Term: **15 Years**(21) Appl. No.: **29/803,644**(22) Filed: **Aug. 13, 2021****Related U.S. Application Data**

(62) Division of application No. 29/647,086, filed on May 9, 2018, now Pat. No. Des. 938,929.

(51) **LOC (14) Cl.** ..... **14-03**(52) **U.S. Cl.**USPC ..... **D14/138 AB**(58) **Field of Classification Search**

Primary Examiner — Llorellys Martinez*Assistant Examiner* — Kwabena A. Ankobiah(74) *Attorney, Agent, or Firm* — Kunzler Bean & Adamson**CLAIM**

The ornamental design for a communication device, as shown and described.

DESCRIPTION

FIG. 1 is a front perspective view of a communication device, showing our new design;

FIG. 2 is a rear perspective view of the communication device;

FIG. 3 is a front view of the communication device;

FIG. 4 is a rear view of the communication device;

FIG. 5 is a first side view of the communication device;

FIG. 6 is a second side view of the communication device;

FIG. 7 is a top view of the communication device; and,

FIG. 8 is a bottom view of the communication device.

The broken lines shown in FIGS. 1-8 illustrate portions of the communication device that form no part of the claimed design.

1 Claim, 6 Drawing Sheets(56)
